[57] ABSTRACT

A container has a rectangular base and two opposite end faces each formed by a rigid frame surrounding a solid wall. Longitudinal members parallel to the longitudinal axis of the base plate connect the upper corners of the end frames. A flexible sheet metal membrane is welded around its entire periphery to the longitudinal edges of the base plate and to the edges of the end frame distinct from the base plate. The membrane passes over the longitudinal members and bears on them without being fixed to them. The external outline of the longitudinal members is shaped in the form of two clothoid portions symmetrical relative to the bisector of the angle formed by the faces defined by the longitudinal members, so that the membrane can slide over them easily without undergoing a sharp bend.

FIG: 4

CONTAINER

The invention relates to a container, more particularly, for example, a container for transport by sea. All containers and, more generally, all rigid packs for transporting material either in bulk or when contained in inner packs, are usually formed by an at least approximately parallelepipedal envelope.

During transport and handling, as a result of acceleration, deceleration or changes of direction, the contents of the container may exert on its faces stresses much greater than the ordinary stresses exerted when the container is at rest on a horizontal plane. For example, the lateral faces of marine containers are required, if the ship rolls, to withstand a force of approximately 0.6 times the weight of the load enclosed in the container.

In conventional containers, each face is constructed so that it can withstand alone the stresses to which it is subjected during transport and handling. The faces are generally formed of a frame surrounding a wall, which may be a fairly thick sheet of fiber-reinforced plywood, a sandwich panel, corrugated iron or ribbed sheet metal. All these panel types are used to form walls because their inherent rigidity enables them to withstand the load, but they are heavy and expensive.

Container walls have also been formed of flat sheets of metal functioning as membranes. These are lighter and more compact than the wall panels mentioned above, so that the effective capacity of the container can be increased. The sheet-metal membrane does not, however, have the strength to resist the internal pressures, all of which are transmitted to the frame surrounding the membrane. The smaller the deformation, the more the pressures transmitted are amplified. The frame is therefore highly stressed, so that its construction must be heavy and expensive.

The invention makes it possible to provide a thin-walled container capable of withstanding the stresses on its lateral faces without excessive reinforcement of its framework, and provides a container comprising a rectangular base plate, two opposite end faces each formed by a frame surrounding a solid wall, elements parallel to the longitudinal axis of the base plate connecting the end frames, and a continuous membrane fixed around its entire periphery to the longitudinal edges of the base plate and to those edges of the end frames distinct from the base plate, the membrane bearing on, but not being fixed to the said elements.

A container according to the invention will now be described, by way of example, with reference to the accompanying drawings.

FIG. 1 is a simplified end view of the container showing how it is deformed by a force applied to a lateral face;

FIG. 2 is a perspective view of the same container, showing how the sheet which forms three faces of the container is fixed to its framework;

FIG. 3 is an expanded view of the membrane sheet forming three faces of the container, showing the distribution of internal stresses as a result of stress applied to a lateral face of the container; and

FIG. 4 gives an example of an external outline for the framework elements on which the membrane bears without being fixed.

As FIGS. 1 and 2 show, the container has a base plate 1 and two lateral faces 2, 3. Each of these lateral faces 2, 3 consists chiefly of a rigid frame formed by vertical end uprights 4 or 5 and upper cross-members 6 or 7 respectively. The other two lateral faces and the roof of the container are formed by a single metal sheet 10 bent around upper longitudinal members 11, 12 and welded around its entire periphery to lower longitudinal members 13, 14 and to the vertical uprights 4, 5 and upper cross-members 6, 7.

When the load inside the container is subjected to transverse acceleration due, for example, to rolling, it exerts a force F (FIG. 1) on the center of one of the lateral faces. This force causes the metal sheet to bulge out and stretch.

In the case of a conventional container, in which the lateral face is a sheet held in a strong frame which defines this face, this force F is balanced by all the tensions T arising in the sheet. If the face is symmetrical it is possible to write, as a first approximation,

$$T = \frac{F}{2 \sin \alpha},$$

a being the angle formed by the deformed sheet with the plane of the wall before deformation. With a sheet of ordinary steel the stretch is small, and it is possible to assume that $\sin \alpha = a$, whence $T = (F/2 a)$.

By contrast, in the case of the novel container described above, the influence of the force F extends to all the three faces covered by the continuous membrane. An identical force therefore causes approximately three times as much stretch in the membrane as is observed in a conventional container. The angle a also increases, though not proportionally, and becomes a' . The tensions T' arising in the membrane may be expressed as $T' = (F/2 a')$, the angle a' being appreciably greater than a , so that the stresses in the membrane of the container are distinctly smaller than those in a conventional container. Figure 3, which shows the sheet 10 expanded flat, indicates, at least qualitatively, the distribution of the stresses applied by the membrane to the fittings supporting it. This distribution does not allow for the reaction from the upper longitudinal members B B' and C C', since except at the ends of these members the deformation of the whole manifests itself only by sliding of the sheet over its longitudinal members. The only result is compressive stressing of these upper longitudinal members, which may be reinforced either with uprights or cross-members or with suitably sited struts to prevent them from bending excessively.

It is therefore important that the sheet 10 should be able to slide freely over the upper longitudinal members B B' and C C'. For this purpose the outline of these longitudinal members is curved. Also, to protect the sheet from alternating deformation as it repeatedly slides over the longitudinal members, a preferred embodiment of the longitudinal members has an external outline whose radius of curvature varies progressively between a very large radius at the point where it joins the flat surfaces and a small radius in its center. The curve representing the external outline of the longitudinal member is therefore composed of two clothoid portions symmetrical relative to the bisector of the angle formed by the two faces.

An approximate indication of such a curve is given in FIG. 4, in which the central portion 1 of the outline is a circular arc of center O_1 , the portions 2 and 2' on each side of this central portion are circular arcs of centers O_2 and O'_2 respectively, the arcs 3 and 3' are circular arcs of centers O_3 , O'_3 , and so on.

At any point of contact between the sheet and the longitudinal member, therefore, the maximum amplitude of the sliding motion of the sheet on the longitudinal member will not cause the radius of curvature to vary more than the sheet can stand without undergoing permanent deformation.

It may be noted, also, that the shape of this external outline of the longitudinal member makes it closer to a right-angle than to a circular arc, so that the volume lost for given overall dimensions is reduced.

Obviously, the invention is not strictly limited to the single embodiment given by way of example, but also covers other embodiments which differ only in detail. For example, the metal sheet forming the membrane, which is welded around its entire periphery, might be replaced with a membrane, not necessarily metal, which is fixed around its periphery not by welding but by any other known means, for example by means of

clamps, hooks or other fastenings, lacing or adhesive. A non-welded construction may make loading of the container faster.

I claim:

5 1. A container comprising a rectangular base plate, two opposite end faces each comprising a frame and a solid wall surrounded by the frame, elements parallel to the longitudinal axis of the base plate connecting said end frames, and a continuous membrane secured around its entire periphery to the longitudinal edges of the base plate and to the edges of said end frames distinct from said base plate, said membrane bearing on, but not being fixed to, said elements.

10 2. A container according to claim 1 wherein said membrane comprises a single metal sheet welded around its entire periphery to the longitudinal edges of said base plate and to the edges of said end frames distinct from said base plate.

15 3. A container according to claim 1 wherein the external outline of said elements has the shape of two 20 clothoid portions symmetrical relative to the bisector of the angle formed by the faces defined by said elements.
